*Primary Examiner—Robin V. Taylor**Attorney, Agent, or Firm—Kelly Bauersfeld Lowry & Kelley, LLP.***[57] CLAIM**

The ornamental design for a hose end trigger spray nozzle, as shown and described.

DESCRIPTION

FIG. 1 is a side elevational view of a hose end trigger spray nozzle embodying my new design, it being understood that the opposite end is substantially a mirror image thereof;
FIG. 2 is a front elevational view thereof;
FIG. 3 is a rear elevational view thereof;
FIG. 4 is a top plan view thereof; and,
FIG. 5 is a bottom plan view thereof.
